UNITED STATES PATENT OFFICE.

AUGUSTUS SMITH, OF NORTH PLAINFIELD, NEW JERSEY, ASSIGNOR TO THE BERGEN POINT IRON WORKS, OF BAYONNE, NEW JERSEY, A CORPORATION OF NEW JERSEY.

LOADING DEVICE.

1,090,658.

Specification of Letters Patent. Patented Mar. 17, 1914.

Application filed December 21, 1911. Serial No. 667,073.

To all whom it may concern:

Be it known that I, AUGUSTUS SMITH, a citizen of the United States of America, and residing at North Plainfield, in the county of Somerset and State of New Jersey, have invented a certain new and Improved Loading Device, of which the following is a specification.

My invention relates to an improved loading or charging apparatus, and particularly to a mechanism for automatically filling the skip car or other transfer container.

In the following description of the device and in the claims, when the expression "hoisting device" is employed, it is to be understood that this expression is employed in a sense broad enough to include not only a vertical hoisting mechanism, but a horizontal or inclined transfer of the load from one position to another. Likewise when the expression "skip" is used this is to be understood as describing a transfer container of any suitable character, whether bucket, car, or otherwise.

25. In the accompanying drawings, Figure 1 is a diagrammatic elevation of one embodiment of my invention; Figs. 2, 3, 4 and 5 are similar views of variously modified embodiments of said invention; and Fig. 6 is 30 a broken elevation showing the conjugate in position to operate the filler harness. Figs. 7 and 8 are diagrammatic illustrations of the differential drum windings for the arrangement shown in Fig. 1; Fig. 9 is a similar view of a take-up device for slack when a plain drum is used in the Fig. 1 arrangement.

The main object of my invention is to operate the skip-filling mechanism (whether 40 this be the opening of the gate to a discharge chute, the tilting of a rotary filler, or other filling device) from the skip hoisting mechanism, the actuation of the filling mechanism being so coördinated with the skip 45 hoisting mechanism that upon the arrival of the skip in proper filling position the continued operation of the hoisting mechanism serves to automatically actuate the skip filling device, while the skip remains 50 stationary or practically stationary. This coöperation and coördination of the hoisting and filling mechanism may be accomplished in various ways and those illustrated are given merely by way of example as several

embodiments of the principle of my invention.

In the forms illustrated I have attained the object specified by a combination of a hoisting mechanism (preferably in the form of a differential drum of the type described in my Patent 929,508) for operating a pair of skips (or a skip and counterweight) and a harness (whether of rope, chain, links or levers) connected to the filling mechanism and so arranged and coördinated with relation to the hoisting mechanism that when the skip to be filled arrives in proper filling position, the conjugate skip or counterweight is in such position that upon the continued operation of the hoisting mechanism the filling mechanism is actuated by the continued travel of the conjugate skip or counterweight after the skip to be filled has come to rest.

In Fig. 1 two conjugate skips 10 and 11 are shown at opposite limits of their respective motion. These skips discharge alternately into the bin 14 after having been filled from the hoppers 15—16 respectively. In the form shown the skip fillers 17—18 are of the rotary type and are controlled by suitable harness, in the form of ropes 19 and 20 secured respectively at one end to said respective fillers and at their other ends to suitable stationary abutments. These ropes 19 and 20 are so arranged in the paths of the respective skips 10 and 11 that when, for example, skip 10 is in filling position, the conjugate skip 11 or some part of it, for example, the pulleys 21—22 on the bail 23, engages the harness 19, controlling the filler 17, and actuates it upon the continued rotation of the drum 13; and vice versa, when the skip 11 is in filling position. In order to avoid interference between the hoisting rope 12 and the ropes 19, and 20 for the filling mechanisms, each of the latter preferably comprises a pair of ropes lying one on each side of the hoisting rope. If a simple cylindrical drum, instead of a differential drum, be used for hoisting, the harness-engaging members might be carried directly by the hoisting rope instead of being mounted on the bail or other portions of the skips. In any case the method of operation is the same, the principle involved being that a member conjugate to the skip being filled engages the harness for actuat-

ing the filling mechanism at approximately the same time (it may be just before or just after) the skip to be filled reaches its filling position and then by its continued motion 5 actuates the filler through its harness. During this continued motion of the conjugate member, the skip being filled remains at rest. This may be accomplished in various ways. If a simple drum be used for hoisting, 10 the skip to be filled may be stopped by any suitable bumper. If a differential hoisting drum be used, as is preferred, the skip will be automatically halted in filling position by so winding the hoisting rope 15 thereon that at the filling position of the skip, the opposite ends of the rope run on and off equal diameters of the drum. In the form shown, the hoist of each skip is the same, but this need not be so, since by 20 operating each skip through a separate hoisting rope and drums of different diameters geared together to insure synchronized rotation, one may be given a greater travel than the other, as will be readily understood.

In Figs. 7 and 8 a differential drum arrangement is illustrated with the hoisting ropes wound thereon to illustrate the skips 10 and 11 of Fig. 1 in their respective dis- 30 charging and loading positions. The loop 12^a carries skip 10 and the loop 12^b carries skip 11. In Fig. 7 skip 10 has nearly reached the upper limit of travel toward dumping position. Upon the reversal of 35 the drive, the right hand side of the loop 12^a pays out and as the rope runs off the larger diameter of the drum it pays out more rapidly than the left hand side of the loop which is winding up on the smaller diameter. Consequently the loop lengthens 40 and skip 10 travels downward. After the right hand side of the rope has run off the larger diameter of the differential, it unwinds from the smaller diameter at the same speed that the left hand side takes up. Consequently the skip is brought to rest. (Fig. 45 8.) While the loop 12^a is lengthening, loop 12^b is shortening by the winding of the left hand end thereof on the larger diameter of 50 its differential, while its right hand end is paying off the smaller diameter. The winding of the loops over their respective differentials is so predetermined at the travel extremes for the skips that while the ends of 55 the loop 12^a are running off and on portions of the same diameter of its differential, (so that the skip 10 is stationary at the bottom of its travel), the ends of loop 12^b are winding off and on portions of different diameters as skip 11 approaches the upper limit 60 of its travel and hence is still in motion, and vice versa. It is this motion of one skip while the other is stationary that is taken advantage of according to the present

invention to actuate the skip filling mechanism. In Fig. 8 for example, after the right hand side of the loop 12^a has run off the large diameter of the differential, the left hand side of loop 12^b has still several turns to run on the larger diameter of its differential, before it reaches its smaller diameter. Consequently skip 11 is lifted while skip 10 65 is stationary.

In Fig. 9 one side of the hoisting mechanism of Fig. 1 is diagrammatically illustrated for an arrangement in which the hoisting rope is wound on a plain drum. Here the continued rotation of the drum after the skip 10 has been stopped in filling position by its abutment, not only lifts skip 11, 70 but results in a slack between the drum and skip 10 which must be taken up. The pulley α is consequently made vertically movable and a counterweight β lifts it as the slack is formed, thus keeping the rope taut. 75 A like arrangement for the skip 11 takes care of its slack, in like manner, when it is halted in filling position, while skip 10 is finishing its upward travel.

The arrangement shown in Fig. 1 is duplex. One of these skips may be replaced by a counterweight 24, if desired, as in Fig. 2, and the operation is precisely the same as in Fig. 1 except that there is of course but a single filler and a single filler harness. 80

In Fig. 3 two skips are employed, but instead of emptying into a common bin, one empties into the other and the latter travels at an angle to the perpendicular, and is discharged at a point spaced horizontally a 85 considerable distance from its receiving position. Here the hoisting rope 25 passes from the hoisting skip 26 up over the loose pulley 27 to the hoisting drum 13, and thence over loose pulleys 28-29 to the conjugate 90 transfer skip 30. The latter travels on the runway 31 which is inclined so that the skip 30 may return by gravity to the position in which it receives its load from skip 26, but it will be understood that any suitable device may be employed to return skip 30 to its receiving position and to keep the hoisting rope taut. The harness 32 for actuating the filler 33 is arranged in the path of the skip 30 and the latter displaces the harness rope while discharging, thus simultaneously filling skip 26, which has come to rest. On the reverse of the hoisting drum 13, the skip 26 rises, as the skip 30 runs down the incline reaching its receiving position as the skip 26 arrives at its point of discharge. Skip 30 is held stationary during the discharge of skip 26, by any suitable means, for example, by the hoisting rope running on and off of diameters of the 100 same size of the differential drum, if the latter be employed.

In Fig. 4 the horizontally traveling trans-

- fer skip 34 is hauled back in one direction against gravity by a rope 35 and counterweight 38 while the hoisting skip 37 is operated in conjunction with said counterweight, the latter serving to operate the filler harness as in Fig. 2. The skip and counterweight are so operated by the hoisting drum that the counterweight reaches the low position and stops before the skip reaches its upper or discharging position, and vice versa. The transfer skip 34 being connected to the counterweight by rope 35 will remain stationary, with the counterweight, while the skip 37 continues to its extreme upper position in order to discharge into said transfer skip.
- In Fig. 5 two horizontally traveling transfer skips 40—41 are shown, discharging alternately into a central bin from independent hoppers. Here the skips move outward under the influence of gravity—in the shape of counterweights 42—43 respectively, the hoisting rope between the skips passing over the hoisting drum 13. The fillers 44, 45 are operated precisely as in Fig. 1 by the discharging skip after its conjugate skip has reached its filling position. Of course the operation of the hoisting drum is precisely the same whether the skips move horizontally or vertically, and I use the expression "hoisting mechanism" in a sense broad enough to include a transfer mechanism whether the transfer is vertical, horizontal or inclined.
- In all of the arrangements illustrated, I have shown the conjugate car or counterweight arranged to pick up a rope or pair of ropes stretched across its path after the manner of a bow string and I prefer this arrangement for the reason that there is little weight in the rope and the initial motion of the gate or filler is infinitely small when the conjugate member first picks up the harness rope. The motion of the filler or gate is gradually accelerated as the conjugate member displaces the harness. This avoids shock. I do not desire to limit my invention to the bow string arrangement however, for it is obvious that if a lever mechanism of any suitable form be arranged in the path of the conjugate it would likewise serve to actuate the gate or filler after the skip to be filled has come to rest in the manner described.
- The essentials of my invention are a hoisting or transfer mechanism arranged to operate two moving bodies one of which is a skip to be filled and the other of which is a conjugate member, so that the conjugate member will continue to move with the hoisting mechanism for a short period after the skip-to-be-filled has come to rest; together with a filler device to charge the skip-to-be-filled, and a harness connected to said filler device and so arranged as to be actuated by the conjugate during its supplemental travel after the skip-to-be-filled has reached its filling position.
- One corollary of the invention is the stopping of the conjugate before the filled skip finishes its travel so that when the conjugate takes the form of a receiving skip, it can be arranged to remain stationary and receive its charge from the filled skip without the loss from spilling which would occur were both in motion. A second corollary of the invention is the fact that the skip and its conjugate are unbalanced during the last few moments of their motion in each direction and the extra load thus thrown on the hoisting mechanism serves to absorb the momentum of the moving parts and bring the hoisting mechanism to rest preparatory to a reversal of the direction of its rotation for the return trip.
- As above stated, the arrangements shown are but illustrative embodiments of my invention and show how it may be variously modified in operating the filler mechanism by means of a conjugate member. Obviously however, various ways of operating the filler from the hoisting mechanism by the continued actuation of the latter after the skip has reached filling position, will readily suggest themselves.
- I claim as my invention:—
1. A hoisting mechanism comprising a skip, means for hoisting the same, and a filler device for charging the skip, in combination with means operated by the continued actuation of said hoisting means after the skip has reached its filling position, for operating said filler device.
  2. A hoisting mechanism comprising a skip, means for hoisting the same, a filler device for charging the skip and a harness controlling said filler device, in combination with means controlled by said hoisting mechanism for engaging said harness, said harness engaging means being brought into actuating position by the continued actuation of said hoisting mechanism after the skip has reached its filling position.
  3. A hoisting mechanism comprising a skip and a conjugate therefor, a filling device for the skip and a harness controlling said filling device arranged in the path of said conjugate and means for moving said conjugate after the skip has reached its filling position, to actuate said filler.
  4. A hoisting mechanism comprising a skip and a conjugate therefor and means for imparting a supplemental travel to said conjugate after the skip has reached its filling position, in combination with a filling device and operating means therefor engaged by said conjugate during its supplemental travel, substantially as described.

5. A hoisting mechanism of the type described, comprising a skip and a conjugate therefor and hoisting rope and drum means for operating the same, in combination with 5 a filling device and operating means therefor arranged in the path of said conjugate member, the winding of said hoisting rope being so arranged as to continue the travel of said conjugate member after the skip 10 has reached its filling position and thus bring said conjugate member into actuating engagement with said operating means for the filling device.
6. A hoisting mechanism of the type described, comprising a skip and a conjugate therefor and means for arresting the travel of said skip in filling position during the continued travel of said conjugate, in combination with a filling device and a harness 15 controlling the operation thereof, said harness being so arranged in the path of said conjugate as to be operated by the latter during the continued travel thereof after the skip has reached filling position.
- 20 7. A hoisting mechanism of the type described, comprising a skip and a conjugate therefor and means for arresting the travel of said skip in filling position during the continued travel of said conjugate, in combination with a filling device and a harness 25 controlling the operation thereof, said harness comprising a rope so arranged in the path of said conjugate as to be engaged by the latter and displaced during the con-
- tinued travel thereof after the skip has 30 reached filling position.
8. A hoisting mechanism of the type described, comprising a skip and a conjugate therefor, a hoisting rope between said skip and its conjugate and means for arresting 35 the skip in filling position during the continued travel of said conjugate, in combination with a filling device and a harness controlling the operation thereof, said harness comprising a pair of ropes so arranged one 40 on each side of said hoisting rope and in the path of said conjugate as to be engaged by the latter and displaced during the continued travel thereof after the skip has 45 reached filling position.
9. A hoisting mechanism of the type described, comprising a skip and a conjugate therefor, a hoisting rope between said skip and its conjugate and means for arresting 50 the skip in filling position during the continued travel of said conjugate whereby the latter overbalances said skip and brakes the hoisting mechanism, in combination with a filling device, a harness therefor engaged by said conjugate during its braking travel, 55 to fill the skip, substantially as described.
- In testimony whereof I have signed my name to this specification, in the presence of two subscribing witnesses.
- AUGUSTUS SMITH.
